(57) **CLAIM**

The ornamental design for a rotary microtome, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, right top perspective view of a rotary microtome with a partial section view taken along line 1-1 on FIG. 2 and according to the present invention;

FIG. 2 is an elevated front right, top perspective view of a rotary microtome according to the present invention;

FIG. 3 is a front view of a rotary microtome according to the present invention;

FIG. 4 is a right side view of a rotary microtome according the present invention;

FIG. 5 is a top view of a rotary microtome according the present invention;

FIG. 6 is a bottom view of a rotary microtome according the present invention; and,

FIG. 7 is a left side view of a rotary microtome according to the present invention.

The broken line showing of the rotary microtome is for the purpose of illustrating portions of the rotary microtome and form no part of the claimed design.
